UNITED STATES PATENT OFFICE.

WILLIAM A. McCOOL, OF PERRYSVILLE, OHIO.

MACHINE FOR DRAWING METALS.

SPECIFICATION forming part of Letters Patent No. 364,126, dated May 31, 1887.

Application filed November 18, 1886. Serial No. 219,344. (No model.)

To all whom it may concern:

Be it known that I, WILLIAM A. McCOOL, a citizen of the United States, residing at Perrysville, Ashland county, State of Ohio, have 5 invented certain new and useful Improvements in Machines for Drawing Metals, of which the following is a specification.

The object of my invention is to provide a machine for drawing metals, in which the grip 10 is so constructed that the greater the strain upon the metal in the grip the tighter will the grip hold the work, and, further, in the guide-rolls for guiding the material into the die while being shaped or reduced.

15 One form of my improved machine is shown in the accompanying drawings, in which—

Figure 1 is a top plan, the track being somewhat broken away to show that the track is not shown at full length. Fig. 2 is a side elevation, the track being similarly broken away. 20 Figs. 3 and 4 are enlarged views of my improved grip, the grip being closed in Fig. 3 and open in Fig. 4. Fig. 5 is a vertical section of the grip when closed. Figs. 6, 7, and 25 8 are details showing different views of the guide through which the metal is drawn to the die and thence to the grip.

The same letters indicate similar parts in the different figures.

30 A is the supporting-frame for the driving mechanism. B is the stand which supports the die. Between A and B runs a box or tunnel, C, on top of which is the track D, and through which passes the drawing-chain E upon its return motion. The carriage F is mounted upon rollers a a and carries the grip G, and is adapted to roll along the track D when it is drawn by the chain E, into one of whose links the hook H is dropped.

40 The driving mechanism consists of a suitable set of interlocking gears, I I, mounted upon suitable shafts, b b, journaled in the frame A, receiving motion from a source of power (not shown) and communicating it through the 45 main wheel J to the shaft c, upon which is mounted the cog-wheel K, the projections of which in its revolution engage the successive links of the chain in the manner usual to chain pumps and gear. A similar wheel at the 50 other end of the tunnel C (shown in dotted lines in Fig. 2) serves to hold the chain con-

tinually taut. The entering guide L contains four rollers, d d, suitably mounted therein, and between these rollers the metal is passed to the die and thence into the grip. This 55 guide is provided with the adjusting-slot e and pin f, the slot being in a bearing secured to the support B, the guide being hung to said support by the pivot g, and the die being stationary just in front of the pivot. This 60 adjustment is to secure the proper level of the metal upon entering the grip, from whatever angle it may come, to the first pair of rollers in the guide.

The grip itself, as shown in Figs. 3, 4, and 65 5, is constructed as follows: The case M has a shelving mouth, the inclined edges of which correspond to similar inclines on the movable jaws N N. These jaws are pivoted together by the pivot h, and are adapted to be thrust 70 forward so as to project partly from the mouth of the case M, in which case the jaws are closed by the action of the inclined edges referred to, under the action of the cam O, which is turned by means of the handle P. It is 75 obvious that when the cam O is turned into the position shown in Fig. 3 the jaws are thrust as far forward as possible and the grip is at its strongest. When the handle is in the position shown in Fig. 4, there is no pressure 80 upon the jaws, which, therefore, are thrown back by the spring S, coiled around the shaft i, and are thrown open by the resilient force of the spring T, thus releasing the metal rod U.

Obviously any intermediate position of the 85 handle P and cam O will give a corresponding tension upon the jaws and regulate the grip upon the metal.

The operation is as follows: The metal to be drawn is passed into and through the die L between the rollers d d into the mouth of the grip G, and then the handle P and cam O are turned to thrust the jaws forward to grip the metal with the desired force. The hook H is then dropped and falls into the nearest link of 90 the chain E and the machine is then started. The revolution of the shaft c and wheel K, by engaging the successive links of the chain, as before described, gradually draws the chain, and with it the carriage F, from B toward A. 100 The end of the metal being firmly held by the grip is of course drawn forcibly through the

die and made to assume the desired character in the way usual in drawing metal. When the metal has been drawn through the die and the carriage has reached the end of its journey, the hook H is lifted clear of the chain, the metal released and removed from the grip, and the carriage is rolled back into position for the next piece of metal.

I claim—

- 10 1. The above-described grip, consisting of the jaws N N, inclosed in a box and adapted to be closed and held together under the control of a cam and to be thrown back and apart

by springs, as herein described, and for the purposes specified.

2. The adjustable entering guide L, provided with suitable rollers and adapted to be raised or lowered to adapt itself to the various directions from which the metal may be fed to it, to insure its always being passed through the grip at a fixed level, as herein described and shown.

15 WILLIAM A. McCOOL.
